OF SAID DAVID S. WILLIAMS, DECEASED, ASSIGNOR OF ONE-HALF TO HENRY
DRUSCHEL, OF COLUMBIA, PENNSYLVANIA.

INTERNAL-COMBUSTION ENGINE.

1,165,366.

Specification of Letters Patent. Patented Dec. 21, 1915.

Application filed January 11, 1912. Serial No. 670,542.

To all whom it may concern:

Be it known that I, DAVID S. WILLIAMS, a citizen of the United States, residing at Glenside, in the county of Montgomery and 5 State of Pennsylvania, have invented certain new and useful Improvements in Internal-Combustion Engines, of which the following is a specification.

The present invention relates to internal- 10 combustion engines for burning liquid hydrocarbon fuel heavier than gasoline such for instance as kerosene having a specific gravity of .807, a flashing point of about 110° Fahrenheit and a burning point of up- 15 ward of 125° Fahrenheit.

The invention relates to the introduction into the cylinder or explosion chamber of an internal-combustion engine of aqueous vapor or steam together with the fuel 20 and air which according to my invention forms therein the explosive mixture.

The method adapted in carrying out my invention consists in the employment of suitable means for generating steam or 25 vapor, which method consists in supplying a liquid to a suitable generator, heating the generator initially by means of a torch or other suitable device and afterward by the heat generated by the explosive mixture so 30 that the small quantity of liquid injected into the generator will be maintained at a temperature of vaporization prior to its introduction into the working cylinder or explosion chamber.

35 The invention further contemplates the employment of a fuel vaporizer constructed and arranged so as to be heated by the steam generator and to discharge a quantity of fuel vapor into the explosion chamber 40 simultaneously with the discharge of vapor from the generator and in varying the supply of fuel and air, or fuel, aqueous vapor and air in substantial unison with the variations of demand for the same and in substantially 45 definite quantitative relation to said variations.

It is therefore the object of the present invention to provide an internal-combustion engine with a steam or vapor generator substantially 50 independent of the water jacket or other means for reducing the temperature of the working cylinder, in means for regulating the supply of liquid to the generator, in means whereby the fuel is vaporized by

the heat of the generator and injected with air into the working cylinder simultaneously with the vapor from the generator in substantially definite quantitative relation to the speed of the engine.

In order to obtain successful results with liquid fuel such as kerosene or other heavier fuel oils the temperature of the cylinder ordinarily must be hot enough to completely vaporize the fuel, yet the temperature must be controlled so that it will not cause the piston to bind in the cylinder or cause pre-ignition of the combustible charge. In ordinary practice it has been the custom when employing kerosene as a fuel to start an engine with gasoline and run it for a time until the cylinder is heated to a temperature sufficient to vaporize kerosene, after which the supply of gasoline is discontinued and the kerosene is then substituted as fuel. In this manner many engines will run for a short time on kerosene as a fuel but sooner or later a deposit of carbon forms on the inner walls of the cylinder which if not promptly removed will cause serious trouble. It is well known to those skilled in the art that when certain complex bodies found in kerosene are subjected to temperatures as high as those found within the walls of the combustion chamber of an internal-combustion engine they appear to break up into more simple compounds. It is believed to be not improbable that many of the more complex bodies contained in kerosene go through some such process of partial decomposition before actual combustion takes place. It is therefore reasonable to suppose that when kerosene is employed as a fuel in an engine under the same conditions as gasoline free carbon is deposited as above explained. On the contrary it has been found that when kerosene vapor is caused to commingle with aqueous vapor particularly with superheated steam together with air and then exploded, combustion is far more complete than when the aqueous vapor is absent.

100 My invention is therefore more particularly addressed to the provision of means to prevent accumulation of deposits of carbon in the explosion chamber and to this end vapor, preferably superheated steam is supplied to the cylinder or explosion chamber without the employment in the generator of any considerable quantity of potentially-

active reserve energy in the form of a large body of highly heated liquid under considerable pressure according to the manner hereinafter fully explained.

- 5 The novel features which characterize my invention are pointed out with particularity in the claims annexed to and forming a part of this specification. For a better understanding of the invention, however, and the 10 advantages possessed by it, reference may be had to the accompanying drawings and descriptive matter in which I have illustrated and described several forms in which my invention may be embodied.
- 15 In the drawing—Figure 1 is a view of an internal combustion engine in side elevation showing my invention as applied to a type known as a horizontal stationary engine. Fig. 2 is a view partly in elevation and 20 partly in longitudinal section through the center of the engine. Fig. 3 shows a front elevation of an internal combustion engine of the vertical type wherein a slightly modified form of my invention is illustrated.
- 25 Fig. 4 is a view in vertical section of Fig. 3, and Fig. 5 is a detached front elevation of one of the fly wheels showing a portion of the governing mechanism.

As shown in Figs. 1 and 2 of the drawings, the cylinder or combustion chamber A is provided with a water jacket A¹ of ordinary construction, a reciprocating piston B, crank shaft C and connecting rod D. The casing A² of the cylinder is preferably extended forward to inclose the crank or crank-disks and to receive the bearings of the crank-shaft C. The piston B is connected to one end of the connecting rod or pitman D by a pin B¹, its opposite end being journaled upon the crank pin C¹, which is carried by crank-disks C², securely fastened to the two parts of the crank-shaft C. The space inclosed by the forward part of the casing A², constitutes a convenient air-compression chamber in which air admitted through a suitable valve A³, during the rearward movement of the piston is compressed at each forward movement of the piston.

50 As the piston approaches the limit of its forward movement and uncovers the exhaust port E, the pressure in the working cylinder or combustion chamber will be discharged, permitting the compressed air to 55 pass along the duct a, and to open the valve A⁴, which controls the admission of air to the combustion chamber. The end wall of the working cylinder or combustion chamber is provided with a generator F, preferably 60 formed integral with the cylinder but which may if desired be cast as a separate piece and bolted to the cylinder after the manner of a cylinder head. The generator F as shown in Figs. 1 and 2 of the drawings 65 comprises an annular chamber formed with-

in the end wall or head of the cylinder entirely independent of the water-jacket surrounding the cylinder except for a fluid pipe or connection under control of a suitable pump by which means a predetermined amount of water is fed to the generator. This method of supplying feed-water to the generator is preferred for the reason that the water reaches the generator at a higher temperature than would be the case if taken from some other source of supply. It will be understood however that other arrangements may be substituted therefor and that feed-water may be taken from any convenient source of supply other than that above mentioned. The fluid supply pipe F¹, leading from the water-jacket A¹ to the generator F, is under control of a pump F² provided with suitable check valves f² and f³ as shown in Fig. 1. The generator F is provided with a nipple f, having a discharge orifice f¹ through which aqueous vapor may pass from the generator to the combustion chamber or cylinder. Mounted upon the generator F is a fuel vaporizer G, one end of which is in communication with a fuel supply tank G¹ through a fuel supply pipe G², while the other end of the fuel vaporizer passes into and through the generator F and is provided with a discharge nozzle G³, coincident with the discharge orifice of the generator. Thus as the generator is supplied with fluid and the vaporizer with fuel a simultaneous discharge of aqueous vapor and vaporized fuel will be emitted from the opening in the wall of the generator. As the air in passing from the compression chamber to the cylinder is conveyed through the duct a, it will absorb some of the heat of the cylinder so that upon reaching the discharge opening in the valve A⁴, the air in a somewhat heated condition will combine with the fuel vapor and aqueous vapor upon entering the cylinder but only to form a mechanical mixture as distinguished from a chemical combination. Under these conditions the finely divided and highly combustible mixture admitted to the combustion chamber is readily ignited and this may be accomplished either by means of an ignition tube H, as shown in Fig. 2 of the drawings or by the conventional spark plug I, as illustrated in Figs. 3 and 4. For convenience of illustration I have shown the fuel supply tank in both the horizontal and vertical types 120 of engines as mounted upon the water-jacket of the cylinder. It is obvious however, that the fuel tank may be located at a point remote from the engine and the fuel conveyed therefrom to the engine by a suitable line of pipe and that the fuel may flow either by gravity or from a tank under pressure as may be desired. In the type of engine shown in Figs. 1 and 2 of the drawings the fuel supply tank G¹, is mounted upon a 125

bracket g^1 , secured to the cylinder of the engine and the fuel is permitted to flow by gravity through one section of the fuel supply pipe G^2 to a pump G^4 and from thence 5 through another section of the fuel supply pipe G^2 to the fuel vaporizer G . It is obvious that the supply of liquid fuel to and from the pump G^4 may be controlled by suitable check valves g^4 and g^5 . While various types of generators in connection with apparatus for carrying my invention into effect may be employed, the best results can only be attained by one in which the liquid is progressively heated from its point of 10 entrance into the water-jacket to the point of exit in the generator where it is substantially all transformed into vapor and in which only a small quantity of liquid is maintained at the temperature of vaporization corresponding for a brief period to the pressure of the working cylinder.

In order to maintain a vaporizing temperature of the fluid the generator must be located in the zone of most intense heat or 25 in one of the heat zones of the engine, one of which is found to be located in the end of the cylinder or combustion chamber and the other at the port of exit of the exhaust. In the construction shown in Figs. 1 and 2 30 of the drawings the generator has been described as placed in the end of the cylinder or combustion-chamber while I shall now proceed to describe a modified form of my invention in which the generator together 35 with the fuel vaporizer are both placed adjacent to the exhaust passage.

In the construction illustrated in Figs. 3 and 4 the cylinder or combustion chamber A^{10} is provided with a water-jacket A^{11} , a 40 piston B^{10} , crank-shaft C^{10} and pitman D^{10} . The cylinder A^{10} , is connected to a casing A^{12} extended downward to inclose the crank A^{13} and to receive the bearings of the crank-shaft C^{10} . The piston B^{10} is connected to one end of the pitman D^{10} by a pin B^{11} and at its opposite end to a crank pin C^{11} of the crank shaft C^{10} . The space inclosed by the casing A^{12} serves as a compression chamber into which air is admitted through 45 a valve a^3 . As the piston reaches the limit of its downward movement as shown in Fig. 4 both the exhaust port E^{10} and the port or terminal of the air duct a^{11} will be uncovered by the piston, the former slightly 50 before the latter as indicated by the position occupied by each relative to the end of the piston.

The exhaust port E^{10} , is provided with an exhaust-head E^{11} , in the end of which is a 55 chamber constituting a generator F^{10} . In the side of the exhaust head is a connection E^{12} , fitted to receive an exhaust pipe E^{13} . The generator F^{10} is provided with a discharge opening to which is fitted a nipple f^{10} . Mounted upon the exhaust-head or that

portion of the exhaust-head constituting the generator F^{10} is a fuel vaporizer G^{10} , connected to a fuel supply pipe G^{11} , leading from a fuel supply tank G^{12} . The vaporizer is provided with a discharge nozzle g^{10} , 70 which enters the nipple f^{10} of the generator, thus making it possible for the fuel supply to be drawn in by induction during the discharge of the vapor from the generator.

Before proceeding to describe the governor mechanism it may be proper to say that while it is desirable to have the supply of aqueous fluid, or the supply of fuel or both vary according to the demand for fuel energy and in definite quantitative relations to variations of load or variation in the speed of the engine, it is not as important that definite quantitative relations should be maintained between the aqueous fluid supply and the fuel supply as between the fuel supply and atmospheric air. Thus for example in the construction shown in Figs. 3 and 4 the quantitative relation between fuel supply and water supply constantly vary for the reason that the same 90 volume of aqueous fluid is fed by a pump to the generator at each stroke of the piston, while the volume of both fuel and air supplied to the cylinder may be caused to vary according to load or variations in the speed 95 of the engine, while in the construction shown in Figs. 1 and 2 of the drawings all of the products admitted to the cylinder are under control of a governor mechanism.

Referring now to the governor mechanism 100 shown in Figs. 1 and 2 of the drawings, K is the governor proper and comprises a frame or support K^1 , bolted to the casing of the engine and provided with a vertical bearing K^2 , forming a journal for a shaft 105 K^3 , which carries a cap K^5 , to which weighted levers K^6 , K^6 are pivotally secured. The weighted levers are in fact bell crank levers the short arms of which engage 110 openings in a sleeve K^4 which sleeve is permitted to slide upon the shaft K^3 when the weighted levers are acted upon by centrifugal force. It is obvious that motion may be transmitted from the crank-shaft C of the engine to the shaft K^3 of the governor 115 by worm gears, etc., and a suitable line of connections including shafts c^1 and c^2 all of which is of well known construction. The bearing K^2 is provided with an arm K^7 , forming one of the bearings for a shaft K^8 , 120 the other of the bearings for said shaft being mounted upon the casing of the engine as shown at K^9 . The shaft K^8 is provided with three levers, to wit, a lever L , which is connected in a suitable manner to a groove in the sleeve K^4 , a lever L^1 connected to a rod L^2 for controlling the valve A^3 and a lever L^3 connecting to a rod L^4 , which in turn is connected to a latch M , controlling the pump mechanism. In order to control the admis- 125

sion of air through the valve port of the valve A³, said valve is provided with a cam plate N, connected to the rod L² and having an inclined face to engage a portion of the valve stem. Thus according to variations in load or variations in the speed of the engine the governor K will act upon the valve A³ to regulate the supply of air to the compression chamber of the engine.

10 The means employed to regulate the supply of fluid fuel and aqueous fluid to the vaporizer and generator is as follows: The fuel pump G⁴ is provided with a plunger O and the pump F² has a similar plunger O¹ both of which are secured to a cross head M¹ adapted to engage the latch M. Secured to the crank-shaft C is an eccentric P, operatively connected to an eccentric lever P¹ journaled at one end to head of a rocking-arm P² which is fulcrumed at a point P² to the casing of the engine. According to this arrangement as variations in the speed of the engine take place, the governor K will cause the latch M to move into or out of the path of the head of the arm P², and thereby disconnect the pumps from the actuating mechanism when the speed of the engine becomes excessive.

15 The governor mechanism illustrated in Figs. 3 and 4 of the drawings is designed to accomplish the same result but in a somewhat different manner. According to this construction K¹⁰ is the governor proper and comprises a weighted lever K¹⁶ fulcrumed at a point K¹⁷ to a fly wheel Q, and normally resting against a pin K¹¹ by the tension of a spring K¹² interposed between the end of the lever and a projection formed upon one of the spokes of the wheel. The weighted lever K¹⁶, is connected by a link K¹⁸ to an arm R of a yoke R¹ which is journaled at a point R² to bearings R³ connected to or forming a part of the fly-wheel. The curved arms of the yoke embrace a sleeve S and are provided with short studs r¹, r¹, which engage a peripheral groove S¹ formed about the sleeve. The sleeve S is also provided with an inclined cam S² adapted to operate a rod T, which rod is provided at one end with a wheel t, to engage the cam S² and at the other forms the stem of a valve T¹, which controls the flow of liquid fuel from the fuel-tank G¹² to the vaporizer G¹⁰. The sleeve S, which is loosely splined to the crank-shaft C¹⁰ as shown in Fig. 5, is also provided with a peripheral groove S¹¹, to receive the projecting ends of a yoke R¹¹, fulcrumed to an arm R¹³, projecting from the flange of the valve a³. The yoke R¹¹, is also provided with an arm R¹², which is connected to a rod R¹⁴, and this rod is in turn connected to a cam-plate R¹⁵ guided upon the valve a³ and adapted to engage the head of a valve stem T¹¹.

20 By the mechanism just described the gov-

ernor may be caused to act simultaneously upon the device controlling the fuel supply and the valve controlling the admission of air to the compression chamber and thereby establish definite quantitative relations between the two according to the demand for fuel energy or as before stated according to variations of load or variations in the speed of the engine. The mechanism for feeding a predetermined amount of aqueous liquid to the generator according to the construction illustrated in Figs. 3 and 4, comprises an eccentric U secured to the crank-shaft C¹⁰ and provided with an eccentric lever U¹ fulcrumed at its uppermost portion to a rocking-arm U², which is journaled upon a stud U³ projecting from the casing of the cylinder. The pump V is provided with a suitable plunger V¹ and with check valves V² and V³, one of which is in line of connection with that portion of the pipe V⁴ leading from the water jacket to the pump while the other is in line of connection with the portion leading from the pump to the generator F¹⁰.

25 The plunger V¹, is acted upon by the eccentric lever U¹ and rocking-arm U², only momentarily and at a time when the eccentric U is near the end of its upward stroke, permitting but a small quantity of aqueous fluid to be forced into the generator, and to pass from thence into the cylinder before the port E¹⁰ is closed by a return of the piston. This latter construction has been found to operate successfully with engines of small capacity and particularly with engines of the so called two cycle type operating at a high rate of speed.

30 While I have shown and described what I believe to be the preferred embodiment of my invention it will be understood that other mechanism of a more or less modified character may be employed with the same object in view, and that my invention may be used in connection with engines of a type other than those herein mentioned without departing from the scope of my invention.

35 Having now fully described my invention what I claim is:—

1. An internal combustion engine comprising a cylinder or explosion chamber, an aqueous vapor generator and means for supplying liquid thereto, a separate vaporizer and means for supplying fuel thereto, said generator and vaporizer having a common discharge communicating with the explosion chamber whereby aqueous vapor and vaporized fuel are caused to commingle during discharge, and an independent air passage opening into the cylinder whereby the air will mix with the vaporized fuel and aqueous vapor only in the explosion chamber.

2. An internal combustion engine comprising a cylinder or explosion chamber, an

- aqueous vapor generator and means for supplying liquid thereto, a discharge opening between said generator and the explosion chamber, a nipple in said discharge opening, a vaporizer and means for supplying fuel thereto, said vaporizer extending through said generator and having a nozzle extending into said nipple, whereby the vaporized fuel will be drawn into the combustion chamber by induction during the discharge of vapor from the generator, and means for independently supplying air to the cylinder. 10
3. An internal combustion engine comprising a working cylinder or explosion chamber, a steam or vapor generator, means for supplying a liquid to the generator, a separate fuel vaporizer, means for supplying a liquid fuel to the vaporizer, means whereby the steam and fuel vapor are caused 15 to commingle while passing into the explosion chamber, and means for independently supplying air to the explosion chamber.
4. An internal combustion engine comprising a cylinder or explosion chamber 20 provided with an air inlet passage and a passage for the discharge of products of combustion, a steam or vapor generator having a fluid supply pipe and a vapor discharge orifice communicating with the explosion chamber, a fuel vaporizer provided 25 with fuel supply and discharge connec-
- tions, the discharge end of the vaporizer extending into and discharging through the discharge orifice of the generator, means for supplying a predetermined quantity of fluid 30 to the generator and means for varying the supplies of air and fuel vapor in substantial unison and in definite quantitative relations to the variations in the speed of the engine. 35
5. An internal combustion engine comprising a cylinder or explosion chamber provided with an air inlet passage and an exhaust passage for the discharge of products of combustion, a steam or vapor generator 40 arranged within the exhaust passage having a fluid supply connection and a vapor discharge orifice and a fuel vaporizer mounted upon the generator and adapted to discharge fuel vapor through the exhaust passage into 45 the cylinder simultaneously with the introduction of aqueous vapor from the generator whereby the aqueous vapor and fuel vapor together with an incoming volume of air are caused to commingle upon entering the cylinder or explosion chamber. 50
- In testimony whereof I affix my signature in presence of two witnesses.
- DAVID S. WILLIAMS.
